UNITED STATES PATENT OFFICE.

LYMAN D. HOWARD, OF COLUMBUS, OHIO, ASSIGNOR TO JOSEPH A. JEFFREY, OF SAME PLACE.

DEVICE FOR LOWERING AND DELIVERING COAL.

SPECIFICATION forming part of Letters Patent No. 545,201, dated August 27, 1895.

Application filed March 2, 1891. Serial No. 383,432. (No model.)

To all whom it may concern:

Be it known that I, LYMAN D. HOWARD, a citizen of the United States, residing at Columbus, in the county of Franklin and State 5 of Ohio, have invented certain new and useful Improvements in Devices for Lowering and Delivering Coal or other Materials, of which the following is a specification, reference being had therein to the accompanying drawings.

This invention relates to an improved mechanism for receiving and temporarily storing or lowering and delivering materials of certain sorts, such as coal, grain, &c. It is well known that in handling, transporting, and piling coal there is much loss incident to the breakage and abrasion of the particles, especially where the coal is allowed to fall a considerable distance, as when delivering it from the cars through the trestles at wharfage points.

The object of the present invention is to provide a means for receiving coal at points where it is to be lowered or piled. The devices I employ can be also used to prevent impairing the appearance and quality of the coal from exposure and preserve the luster and freshness of appearance, which, as is well known, enhances its marketableness.

The essential features of the invention can be embodied in several forms. In the drawings I have shown some of the simple forms of devices adapted to carry it out.

Figure 1 is a top plan view of a mechanism embodying my invention. Fig. 2 is a side view of the chute-sections. Fig. 3 is a vertical section of one of the chute-sections. Fig. 4 is a side elevation of a mechanism similar to that in Fig. 1, it having a modified form of guide and suspending device. Fig. 5 is a top plan view of the tube-section shown in Fig. 3. Fig. 6 is a section on line $\alpha\alpha$, Fig. 2.

A A' A² represent a series of vertically movable chute-sections, A' being the top one 45 of the series, A² the bottom one, and A A the intermediate. They may be of any suitable shape, dimensions, and capacity. Preferably they are constructed so as to easily telescope one with another. They may be circular or 50 angular in section and cylindrical in general form or otherwise shaped. As shown, each is

of the form of a frustum of a cone, all being substantially equal in size and capacity. They are open at bottom and top. Each is provided at the upper end with an exterior ring H, 55 which not only strengthens the chute-section, but also can be utilized for carrying guides, suspending devices, stops, &c.

G' G' are arms extending outward from the sides of the ring on the bottom cone A² and 60 adapted to have one or more cables, chains, or other suitable supporting means attached.

The cable shown at K passes over sheaves, such as that at N, and thence to an engine 65 for lifting the vessels.

The chute-sections can be suspended from each other, if desired, in such way that when they are lowered each will be stopped and held at a predetermined place, but from which it can be lifted upward as soon as those below 70 it have been drawn up far enough to come into engagement with it. This can be done by connecting each to the next by two or more chains; but when very heavy materials—such as coals—are to be manipulated it is desirable 75 to provide a lateral-support bracing and guiding for the series of chute-sections supplemental to the vertical support above described. For this I prefer to employ one or more rigid guides, each having a beam G, arranged 80 to prevent the chute-sections from swaying laterally in either direction. In the construction shown this is accomplished by providing each chute-section with a plate or arm B opposite each guide G and bearing against it. 85

In Fig. 1 there are two guides G G diametrically opposite and two plates B B, the guides being supported by a frame having posts E E and girts F F and the chute-sections A A' A² being at the center vertically of this frame. 90 The plates or arms B are recessed or have extensions C C, which lie by the sides of the guides G and act to still further steady the vessels.

In Fig. 4 a mechanism is shown having only 95 one rigid guide G, the chute-sections being connected on the opposite side by chains M', secured at the ends to eyes M. The rests for the chute-sections are provided by brackets J, each adapted to engage with one only of 100 the vessels. This can be readily done by having the recesses in the end of the plates B on

each chute-section extend inward a little farther than that on the one above and having the rests or stops J situated gradually nearer the center of the vessel. As shown, the edge 5 of the guide G is inclined inward and downward, so as to bring the stops J to the desired points. It will be seen that when the series of chute-sections is lowered the lower ones will all pass below the upper stops J; but the 10 upper one will engage it and rest upon it till all are again elevated, and the same is true of each in turn. The ends of the parts C can bear against vertical flanges II, formed on or secured to the guide bars G.

15 What I claim is—

1. In a coal lowering or piling mechanism, the combination of an upper supporting frame, a downwardly extensible delivery duct formed of a series of duplicate conical downwardly narrowing sections, the upper section supported from said frame, one or more ropes extending downward to the bottom section and adapted to elevate the sections below the upper one, a guide or brace for preventing 20 lateral movement of the sections, and stops for preventing the sections from escaping respectively one from the other.
2. In a coal lowering or piling mechanism, the combination of the top supporting frame, 25 a downwardly extensible duct formed of overlapping sections with the upper section supported from said frame, one or more ropes se-

cured to the lower section for elevating it and lifting those above it, the movable sections of said series being provided at their upper ends 35 with laterally extending guide or brace arms, one or more stationary guides or braces at the sides of the said sections, and stop devices on each movable section engaging with stop devices on the section above it to limit their 40 relative movements, substantially as set forth.

3. In a coal lowering or piling mechanism, the combination of the top supporting frame, a downwardly extensible tubular delivery duct formed in separate overlapping telescopic 45 sections, each section having a tubular body and one or more laterally extending supporting projections, one or more vertical series of stationary supports or rests, each of said series being adapted to engage with one of 50 the supporting projections on a section of the delivery duct, and an elevating rope connected to the lowermost section, whereby each section can be vertically supported independently of the others, but they can all be elevated together when the bottom one is lifted, 55 substantially as set forth.

In testimony whereof I affix my signature in presence of two witnesses.

LYMAN D. HOWARD.
